UNITED STATES PATENT OFFICE.

DAVID H. WOLFE, OF NODAWAY TOWNSHIP, PAGE COUNTY, ASSIGNOR OF
ONE-HALF OF HIS RIGHT TO N. L. VAN SANDT, OF CLARINDA, IOWA.

GATE.

SPECIFICATION forming part of Letters Patent No. 228,966, dated June 15, 1880.

Application filed June 30, 1879.

To all whom it may concern:

Be it known that I, DAVID H. WOLFE, of the township of Nodaway, county of Page, and State of Iowa, have invented a new and 5 useful Improvement in Gates, of which the following is a specification.

My invention consists of a crane formed of one horizontal bar extending from the upper hinge in the gate-post to a little more than 10 half the length of the gate and another bar extending diagonally from the lower hinge in the gate-post to near the outer end of the first-named bar, where the two are securely fastened together, so that the outer end of the 15 crane may be firmly supported. Upon the outer end of the crane is placed a short cross-bar, upon which is placed a roller.

The gate-posts at rear end of the gate are connected by a short cross-bar near the lower 20 hinge in the post. Upon this cross-bar is placed a roller, which turns on a pivot in the cross-bar. The gate being placed upon these rollers with one of the upper bars resting on the roller at the outer end of the crane and 25 one of the lower bars resting on the roller in the cross-bar between the posts at rear end of the gate renders it unnecessary to lift or carry it when opening or closing it. The gate being entirely supported upon the rollers and the 30 crane attached to the post by hinges, it may be run back to admit persons to pass through, or may be swung open its entire width.

Figure 1 in the accompanying drawings represents the gate closed, and shows the crane 35 with the roller on its outer end, and also the roller on the cross-bar between the posts at rear end of the gate. Fig. 2 represents the crane as attached by hinges to the gate-post, and also shows the rollers upon which the 40 gate is supported. Fig. 3 shows the short cross-bar on outer end of the crane, with the roller fixed upon it for support of the gate.

A A are the bars of the gate; B B, the uprights. C C C are the gate-posts. D D are

the two bars of the crane; H H, the hinges 45 by which it is attached to one of the posts. E is the cross-bar between the posts at the rear end of the gate. F F' are the rollers upon which the gate rests and is supported.

The object of my invention is to give support to the end of the gate in the operation of opening and closing it, so that it shall not be necessary to lift or carry the end of the gate when opening or closing it, whether it be but partly opened or swung open its entire width. 50

To accomplish this object I place the two posts C C at the rear end of the gate far enough apart to allow the gate to slide freely between them, and connect these posts by a short cross-bar, E, and upon the center of this cross-bar the roller F, which turns on a pivot in the cross-bar. Then I fasten the bars of the crane to the post C by the hinges H H, and upon the small cross-bar I place the roller F' at the outer end of the crane. Then placing the gate 65 with one of its lower bars at the rear end resting on the roller F, and one of its upper bars near the middle resting on the roller F', it is held firmly in place, and may be run backward or forward, or swung open or shut without lifting or carrying the end of the gate. 70

Having thus fully described my invention, I claim—

The combination, with a gate, of the crane D D, with its outer end provided with a pulley or sheave wheel, F', the posts C C, disposed one in a plane just in rear of the other, and having a cross-bar, E, with one end or side secured against the rear side of one post, while its other side is secured against the 80 front side of the other post, and swiveled pulley or sheave wheel F, supported in the bar E, as shown and described.

DAVID H. WOLFE.
